UNITED STATES PATENT OFFICE.

CHARLES W. HILLENBRAND, OF KANSAS CITY, KANSAS, ASSIGNOR TO
KATHERINE ELIZABETH BARNES, OF KANSAS CITY, MISSOURI.

TURN-TABLE.

No. 838,329.

Specification of Letters Patent.

Patented Dec. 11, 1906.

Application filed November 20, 1905. Serial No. 288,105.

To all whom it may concern:

Be it known that I, CHARLES W. HILLENBRAND, a citizen of the United States, residing at Kansas City, in the county of Wyandotte and State of Kansas, have invented certain new and useful Improvements in Turn-Tables, of which the following is a specification.

My invention relates to improvements in turn-tables; and my object is to provide an appliance for use in garages or manufactories whereby motor-cars or other vehicles may be turned, as upon a pivot, in any direction.

The invention consists in the novel construction, combination, and arrangement of parts hereinafter described, and pointed out in the claims, and in order that it may be fully understood reference will now be made to the accompanying drawings, in which—

Figure 1 represents a plan view of the turn-table. Fig. 2 is a central longitudinal section taken on line II II of Fig. 1. Fig. 3 is a plan view of a truck-frame employed in carrying out the invention. Fig. 4 is an irregular longitudinal section of a latch and a portion of a runway employed in carrying out the invention, said section being taken on line IV IV of Fig. 5. Fig. 5 is an irregular longitudinal section of said latch, taken on line V V of Fig. 4. Fig. 6 is a vertical section taken on line VI VI of Fig. 5. Fig. 7 is a vertical section of the central post and a casting employed in carrying out the invention, said section being taken on line VII VII of Fig. 1.

In carrying out the invention I employ a track 1, preferably annular in plan view and made in sections 2, so that it may be taken apart and crated for transportation. Said sections are provided at their opposite sides 40 with laterally-extending ears 3 for the reception of lag-screws, whereby the track may be reliably secured to the upper surface of floor A.

4 designates a plurality of trucks (preferably four in number) made in skeleton form, each truck being provided with a pair of parallel flanges 5, a laterally-extending socket 6, two pairs of arms 7, provided at their outer ends with bearings 8, and a diagonally-extending arm 9, provided at its outer end with a sleeve 10.

11 designates a plurality of conical-shaped rollers mounted upon axles 12, arranged in bearings 8.

13 designates a pair of parallel runways securely fastened to flanges 5 by means of bolts 14. The curved ends of said runways are struck from a common center and have their upper corners armed with angle-irons 15, so that said corners will not become worn or chipped by vehicles running upon or leaving the runways. In order that a vehicle may be readily run upon or off of said runways, I provide inclined approaches 16, armed at their lower outer edges with shoes 17 and at their upper inner corners with angle-irons 18 to prevent damage to said corners by vehicles passing thereover. Approaches 16 are held in alinement with the ends of the runways, when the latter occupy their normal position, by brackets 19 and a keeper 20, secured to the floor and provided with centrally-disposed inclined guides 21-20^a, respectively. (See Fig. 1.)

Guide 20^a has a notch 20^b for the reception of the free end of a gravity-latch 22, loosely mounted upon a stud 23 and provided at its opposite end with a foot-piece 24. The pivotal movement of said latch is limited by stops 24^a, integral with the ends of a segmental rib 25, projecting from one end of a plate 26, secured to one edge of one of the runways by screws 27, a rod 28, a washer 29, and a nut 30, engaging the threaded outer end of the rod. Rod 28 extends through a central longitudinal opening in stud 23, which latter projects centrally from plate 26 and is provided with a shoulder 31 to prevent a washer 32, fitting over the reduced portion of said stud, from being pressed into frictional contact with the latch, when the latter is in its normal position, by means of a coil-spring 33, interposed between washers 29 and 32. Latch 22 is provided with a segmental groove 34, which embraces rib 25, and thus prevents the latch from shifting longitudinally on the stud. This construction also permits the latch to rock slightly on the rib when its free end contacts with keeper 20, and thus relieves said free end to a certain extent of the shock to which it is subjected when stopping the turn-table in alinement with the runways. This rocking motion is limited by the latch pressing backwardly against spring 33, which latter is compressed by reason of the fact that the momentum of the runways will carry their curved ends slightly beyond the adjacent ends of the ap-

proaches. When the spring expands, it will move the runways backwardly until their ends register with the adjacent ends of the approaches.

5 In order that the runways may be locked after turning a half-revolution, I provide each runway with a latch 22, as shown in Fig. 1.

35 designates a post placed at the center of track 1 and provided with a base 36, having integral lugs 37, secured to the floor by screws 38.

39 designates a casting provided with a hub 40, swiveled upon post 35, upon which latter it is held by means of a cap 41, a king-bolt 42, extending upwardly through the post and the cap, and a clamping-nut 43, engaging the upper threaded end of the king-bolt. Hub 40 is of less height than post 35, so that 20 the cap will not be forced by the clamping-nut into frictional engagement with said hub, and thus prevent it from freely rotating upon the post.

Casting 39 is provided with four diagonally-arranged arms 44, projecting from the hub and provided at their outer ends with sleeves 45 for the reception of the inner ends of tie-rods 46, the outer ends of which extend through the sleeves 10. Said rods are 30 drawn to the requisite tension by means of nuts 47 and then securely locked in the sleeves by nuts 47 and jam-nuts 48. These rods serve to hold the trucks upon track 1. The trucks are united in pairs by two transverse bars 49, having their ends reliably secured in sockets 6 by bolts 50.

In practice the ends of the runways are normally held in alinement with the adjacent ends of the approaches by one of the latches 40 22, engaging the notch in keeper 20. After a vehicle has been run upon the runways it may be turned in a reversed position by disengaging the latch from the keeper, which may be readily done by pressing one foot 45 downwardly upon the foot-piece 24. The runways may then be revolved until the latch upon the other runway automatically engages the keeper. While the runways are being turned the free ends of the latches are 50 prevented from engaging the sides of the approaches by guides 21, which will direct said free ends to the upper surface of angle-irons 15, so that the free ends of the latches may pass over the same without checking the 55 movement of the turn-table.

Having thus described my invention, what I claim, and desire to secure by Letters Patent, is—

1. In a turn-table, a track, trucks arranged to travel in a circle thereon, a pair of runways mounted upon said trucks, and a pair of inclined approaches with which the ends of the runways are adapted to register.

2. In a turn-table, a track, trucks arranged

to travel in a circle thereon, a pair of runways 65 mounted upon said trucks, a pair of inclined approaches with which the ends of the runways are adapted to register, and means for locking the runways in alinement with said approaches.

3. In a turn-table, a track, trucks arranged to travel in a circle thereon, a pair of runways mounted upon said trucks, said runways having curved ends struck from a common center, and inclined approaches with which 75 the ends of the runways are adapted to register, the adjacent ends of said approaches being curved to correspond with the curved ends of the runways.

4. In a turn-table, a track, trucks arranged to travel in a circle thereon, a pair of runways mounted upon said trucks, said runways having curved ends struck from a common center, angle-irons secured to the upper corners of said curved ends, inclined approaches with which the ends of the runways are adapted to register, the adjacent ends of said approaches being curved to correspond with the curved ends of the runways, and angle-irons secured to the upper corners 90 of said curved ends.

5. In a turn-table, a pair of runways rotatably mounted, inclined approaches with which the ends of the runways are adapted to register, a gravity-latch carried by one of 95 said runways, inclined guides at the sides of the approaches for guiding the latch to the upper surface of said approaches, and a keeper adapted to be engaged by said latch.

6. In a turn-table, a pair of runways rotatably mounted, a plate secured to one of said runways, stops integral with said plate, a stud projecting from said plate, a gravity-latch loosely mounted upon said stud and extending between the stops, means for 105 yieldingly holding said latch upon the stud, and a keeper adapted to be engaged by the latch.

7. In a turn-table, a pair of runways rotatably mounted, a plate secured to one of said 110 runways, a segmental rib integral with said plate, stops integral with the ends of said rib, a stud projecting from said plate, a gravity-latch loosely mounted upon said stud and extending between the stops, said gravity-latch being provided with a groove for the 115 reception of the segmental rib, means for yieldingly holding said latch upon the stud, and a keeper adapted to be engaged by the latch.

8. In a turn-table, a track, trucks arranged to travel in a circle thereon, a pair of runways mounted upon said trucks, a post located at the center of the track, a member provided with a centrally-disposed hub swiveled upon 125 the post, diagonally-arranged arms projecting from said hub, sleeves integral with the outer ends of said arms, and tie-rods secured

at their opposite ends to said sleeves and the trucks.

9. In a turn-table, a track, trucks arranged to travel in a circle thereon, a pair of runways mounted upon said trucks, a post located at the center of the track, a member provided with a centrally-disposed hub swiveled upon the post, diagonally-arranged arms projecting from said hub, sleeves integral with the outer ends of said arms, and tie-rods adjustably secured at their opposite ends to said sleeves and the trucks.

10. In a turn-table, a track, trucks arranged to travel in a circle thereon, sockets integral with said trucks, transverse bars having their ends connected to said sockets, and runways mounted upon said trucks.

11. In a turn-table, a track, trucks arranged to travel in a circle thereon, parallel flanges on said trucks, and runways secured to said flanges.

12. In a turn-table, a track, trucks arranged to travel in a circle thereon, arms arranged in pairs and forming part of said trucks, bearings integral with the outer ends of said arms, axles arranged in said bearings, and wheels forming part of the trucks and mounted upon said axles.

13. In a turn-table, a track, trucks arranged to travel in a circle thereon, diagonally-extending arms integral with said trucks, a post located at the center of the track, a member swiveled thereon, and tie-rods connecting said member to the diagonal arms.

35 14. A vehicle turn-table, comprising parallel runways, struts between them, adjustable tension members connected to the runways for holding them in engagement with

the struts, and supporting-wheels on the runways.

15. A vehicle turn-table, comprising connected parallel runways, supporting-wheels and bearings therefor arranged at the sides of the runways and above their lower surfaces.

16. In a turn-table, the combination with two parallel runways and transverse bars located between them, a post arranged between the runways, tie-rods extending radially from the post to the runways, and wheels located at the inner and outer side of each end of said runways, having their axes disposed radially of a center common to both runways.

17. In a turn-table, the combination with parallel runways mounted upon trucks, and transverse bars located between the runways, of tie-rods connected to the trucks and operating to draw the runways relatively toward each other, and supporting-wheels on the trucks.

18. A turn-table for vehicles comprising two parallel connected runways adapted to receive the wheels of a vehicle and supporting-wheels arranged in pairs at the ends of the runways, one of each of said pairs of supporting-wheels being arranged at an angle to the runway at the inner side thereof and the other similarly positioned at the outer side of the runway.

In testimony whereof I affix my signature in the presence of two witnesses.
